ABSTRACT

Concrete benches and the like are made by assembling
legs and a seat portion. The legs are hexagonal in struc-
ture and the outside surfaces of the seats are indented
so that each fits over and against one of the legs.

CONCRETE FURNITURE

This is a continuation, of application Ser. No. 58,979 filed July 28, 1970 now abandoned.

This invention relates to concrete furniture and particularly seats and benches, and includes a planter or the like which forms a leg portion for one or more benches.

A characteristic of the furniture is that the leg portions are made separately and are generally hexagonal although this may be modified to accommodate adjoining seats. The outer surfaces of the ends of the seat portions are indented and the legs fit into these indentations.

The seat may be made for a single person or it may be made in the form of a bench with or without a back. It may be a double or triple seat. In fact, it may be of any desired length with intermediate supports as required.

A particularly attractive arrangement is to combine one or more seats with a planter, using one or more of the walls of the planter to serve as a leg. The indented seat end thus rests on a wall of the planter which fits into the indentation. The planter may comprise three or more sides but it usually will be four-sided. For a large park, for example, a planter or a fountain or the like may comprise six or eight or more sides with seats radiating from it, and the flat sides which serve as legs may be joined by portions which are curved or otherwise shaped.

The invention is further described in connection with the accompanying drawings, in which

FIG. 1 is an exploded view in perspective of a seat for a single person;

FIG. 2 is a perspective view of the assembled seat of FIG. 1;

FIG. 3 is a section on the line 3—3 of FIG. 2;

FIG. 4 is a perspective view of two benches with one end of each supported on a double leg; and

FIG. 5 is a section through the double leg of FIG. 4 and a portion of one seat supported thereby.

Referring to the drawings, the two legs 5 are identical. The seat portion 6 is provided with a back, but this is not necessary. The outer surface of each of the end portions 8 and 9 of the seat are indented over a rectangular area so as to fit snugly over and against the top parts of the two legs 5. The indentations are each as wide as the legs are wide and they are each about one-half as deep as the legs are thick, although this may vary. The outer surface of the leg may be flush with the outer surface of the seat. The legs are taller or shorter and the indentations accommodate the seat portions so as to support the seats themselves at a comfortable height. The seats may slope backwardly and in that event a drain or a plurality of drains are provided at the one or more low portions of the seat. The drains may be at the back two corners if the seat is flat, but if the seat slopes toward the middle the drain may be at the middle of the seat. If the seat has no back, it may slope in from its longitudinal edges to one or more drains in its middle. In fact, the drain opening may be at the middle of the seat if the seat slopes into it.

FIGS. 4 and 5 show a double leg supporting two seats at right angles to one another. The angle, of course, may be greater or less than 90°, as desired. The two leg portions 15 and 16 are shown at right angles to one another and the rear is notched at 17 to provide edges for

each leg to fit into the depressions in the ends of the seat portion. The front surface 18 opposite the notch is angled to provide sufficient width at the thinnest portion of the element to give the desired strength. This surface 18 is shown as being perfectly flat, although it may be rounded more or less.

The seat portions assembled with this double leg portion are of the same design as described. The end surfaces are indented as described, to fit snugly over the leg portions 15 and 16, and the opposite ends of the seat are supported by legs such as the legs 5 of FIG. 1.

The various elements of the leg are molded of concrete and can be shipped in a knocked-down condition to be assembled at their final location. Usually the bottoms of the legs are buried in the ground or concrete or other surface surrounding the seat so that no adhesive or other bonding is required. The concrete may be reinforced as desired, but no reinforcement is essential. Although the leg surfaces are shown as flat and this is the desired construction, they may be vertically fluted or otherwise designed, and the indentations in the ends of the seats will usually be provided with complementary designs so that the seats fit snugly in the indentations in the seat portions.

By having the depression in the seat ends only half as deep as the feet are wide, it is possible to support two seat ends on a single leg.

I claim:

1. A seat which comprises a horizontal concrete seat portion with an integral upright at both ends, a support at each end of the seat portion, the lower portion of the outside wall of each upright being indented a distance from the side edges thereof, each indentation extending upward from the bottom edge of the respective walls to complement the shape of a support for the seat portion.

2. The seat of claim 1 which has a concrete back which is integral with the seat portion and said ends.

3. The seat of claim 1 in which the support at one end is a hexagonal concrete leg which is thicker than the depth of the indentation.

4. The seat of claim 1 in which the end supports are identical hexagonal concrete legs which are thicker than the indentations in the outside walls of the uprights and fit into said indentations.

5. The seat of claim 3 in which the support at the other end of the seat portion has a rectangular face which fits flush against the bottom of the depression in the upright at said end.

6. A concrete seat assembled from two substantially right-angular, hexagonal concrete leg portions and a concrete seat portion, the seat portion comprising two integral end uprights the outer surfaces of which uprights are identically indented to complement the inner edges and top surfaces of the respective upper parts of said two leg portions, the upper surfaces of the indentations resting for support on the upper surfaces of the leg portions with inner surfaces of the leg portions fitting snugly against the bottoms of said indentations.

7. A concrete seat assembled from a double leg portion, two single leg portions and two seat portions, the double leg portion comprising two exposed vertical rectangular surfaces on the outer surface thereof, said surfaces being at an angle to one another with a vertical notch extending the height of the double leg portion between said two rectangular surfaces, and opposite said notch a reinforcement which joins the two vertical inner surfaces opposite said rectangular outer surfaces

whereby the portion of the seat adjacent the angle of the notch is substantially the same thickness as the two leg portions, the two individual leg portions being substantially right-angular and hexagonal and formed with two exposed rectangular surfaces identical in size with

5

said outer surfaces of the double leg portion, and two seat portions each having two upright ends which are indented to fit over the double leg portions and form a snug fit therewith.
